Edmund G. Borden

UNITED STATES PATENT OFFICE.

ROBERT G. GRISWOLD, OF WESTFIELD, NEW JERSEY, ASSIGNEE TO DOHERTY RESEARCH COMPANY, OF NEW YORK, N. Y., A CORPORATION OF DELAWARE.

PRESSURE-REGULATING, DEMAND-LIMITING, AND VOLUMETRIC METER.

Application filed July 14, 1923. Serial No. 651,483.

My invention relates to the art of metering the volume and regulating the flow of gas.

The novel features of my invention are pointed out with particularity in the appended claims. The invention itself, however, together with the several objects and advantages therein, will best be understood from the following description taken in connection with the accompanying drawing in 10 which:

Fig. 1 is a plan view of an apparatus according to my invention;

Fig. 2 is an elevational view of the apparatus illustrated in Fig. 1, parts being broken 15 away and parts being shown in section for purposes of illustration;

Fig. 3 is a side view of the apparatus illustrated in Figs. 1 and 2, parts being broken away and parts being shown in section for 20 purposes of illustration.

In the drawing 40 is a casing which may conveniently be made of cast iron or of thin tinned iron sheets soldered together as in the ordinary "tin" gas meter. According to my 25 invention I place within casing 40 the major portion of the mechanism 42 of a volumetric gas meter. This may conveniently be of the ordinary bellows type, as illustrated. Above casing 40 is a casting 44 providing an upwardly opening chamber 46 within which is the valve mechanism 48 of the meter mechanism 42. Above casting 44 is casting 50 having a downwardly opening chamber 52 on its lower portion communicating freely with 30 the valve chamber 46. Casting 50 is provided with upwardly extending gas inlet 54 and gas outlet 56. The gas entering the inlet 54 passes downwardly into chamber 52 through a valve seat 58 cooperating with which is a 35 combined pressure regulating and demand limiting inlet valve 60. From the chamber 52 the gas passes thence through a meter mechanism in the ordinary way, and then into an outlet passage 62, running from the out- 40 let side of the meter mechanism 42 in the casing 40 up through the castings 44 and 50. At the upper end of the passage 62 is a plug 64 in which is a demand limiting orifice 66. The gas passing from the meter through passage 62 and orifice 66 issues into a chamber 68 in free communication with the outlet passage in the outlet 56 previously mentioned. As clearly illustrated, the plug 64 is ar- 50 ranged to be inserted through the chamber 68

and screwed into place, the chamber 68 being afterward closed by a threaded cap 70.

As clearly appears from Fig. 2, two spaced diaphragms 72 and 74 are mounted one above the other in the upper portion of the casting 50 to provide a chamber 73 between them. The lower of these diaphragms 72 is exposed to the pressure of gas in the chamber 52, and the upper surface of the upper diaphragm 74 is exposed to atmosphere which enters freely through a cap 76 secured to the top of casting 50, the cap 76 having aperture 77 therein for the purpose of admitting atmospheric pressure. The space or chamber 73 intermediate the diaphragms 72 and 74 communicates with the outlet passage in outlet 56 by means of a conduit or passage 78. As appears clearly from Fig. 2 also the valve 60 is connected to be operated by diaphragms 72 and 74. A spindle 80 on which the valve 60 is mounted being pivotally connected to one end of a lever 82, pivoted at 84, and the other end of the lever 82 being pivoted in turn at 86 to a stem 88 connected to diaphragms 72 and 74. The connection between diaphragm 72 and spindle 88 may be rigid if desired, but the connection between spindle 88 and diaphragm 74 must be a lost motion connection. It often becomes necessary, according to the present invention to control the valve 60 independently of diaphragm 74 and I have illustrated this connection as being formed by an enlarged head 90 on the upper end of the spindle 88 and resting in a socket or chamber 92 formed within the weight or plate 94 fixed to the diaphragm 74. Not only is the diaphragm 74 weighted by the plate 94 but the diaphragm 72 is preferably stiffened by the weight 96. It has been found also that an apertured partition 98 intermediate the two diaphragms 72 and 74 prevents hunting or chattering of the diaphragms and valve 60 when the diaphragms are subjected to rapid changes of pressure.

The meter construction outlined above is used to perform three distinct functions or operations namely: (1) to limit the quantity or volume of gas which may pass through the apparatus in a predetermined unit of time hereinafter referred to as limiting the demand; (2) to measure the volume of gas passing through the meter and (3) to deliver the gas at the outlet at a predetermined pressure when the volume of gas flow per unit of time is below and up to the demand limit. The

valve 60 is operated to control the demand limit of the gas and to control the pressure at which the gas leaves the meter.

The usual meters used in measuring volume or quantity of gas are built as units which have predetermined capacities. For example the common "3-light meter" has a capacity of approximately 114 cubic feet per hour; a "5-light meter" has a capacity of approximately 158 cubic feet per hour; and a "10-light meter" has a capacity of approximately 275 cubic feet per hour. Meters made by different manufacturers vary somewhat in the capacity delivered per hour. In all of these meters the measuring equipment is usually so calibrated that the difference in pressure between the inlet and outlet of the gas or the pressure drop through the meter when measuring full capacity is one-half an inch in water pressure. In substantially all of the dry meters now manufactured the pressure drop across the measuring mechanism varies substantially as the square of velocity of flow of gas being measured or delivered by the mechanism. A 3-light meter would be used, for example, if it was desired to use a meter which would deliver a gas demand limit of fifty cubic feet per hour. To adapt a 3-light meter so that it will deliver the desired fifty cubic feet per hour an orifice plug 64 is provided with a proper size of orifice to deliver 50 cubic feet per hour while maintaining a pressure differential at opposite sides of the diaphragm 72 of one-half an inch of water and to deliver gas through the outlet 56 at a pressure of three inches of water. The outlet pressure of three inches is determined more directly by means of the size and weight of the plate 96 attached to the bottom of the diaphragm 72, the plate 94 attached to the bottom of the diaphragm 74 and the spindle 88. The combined weight of these parts acts in opposition to the pressures exerted on the bottoms of diaphragms 72 and 74 to operate the valve 60 to throttle the pressure of the gas passing through the inlet so that the gas will pass through the measuring mechanism and orifice 66 and be delivered at the outlet 56 at the desired pressure. The pressure regulating devices act to control the pressure at the inlet of the measuring mechanism so that the gas is measured at a pressure which has the minimum difference from the pressure at which the gas is delivered to a customer. The volume of gas passing through the meter is controlled directly by the resistance or pressure drop of the gas passing through the measuring mechanism. The supplemental resistance of the flow of gas through the orifice 66 acts to build up a sufficiently large pressure differential across the diaphragm 72 to positively operate the valve 60 when the demand limit is reached.

With this arrangement the flow of gas through the meter, when below the demand

limit or below the volume which it is desired that the consumer shall use per hour, will be at such a rate as to provide a pressure in the chamber 73 which will lift the weights 96 and 94, the spindle 88 and the diaphragms 72 and 74 and operate the valve 60 to throttle the gas pressure in the chamber 52 so that the pressure in outlet 56 will be the desired maximum. The pressure difference on opposite sides of diaphragm 74 or the difference between atmospheric pressure and the pressure in chamber 73 is always more than enough, during an operation of the meter below the demand limit, to lift the diaphragm 72 and connected parts and positively operate the valve 60. As the volume of gas passing through the outlet varies from zero up to the demand limit both of the diaphragms 72 and 74 will be operated in accordance with the difference between atmospheric pressure and the pressure existing in the chamber 73 to deliver the gas at a uniform pressure and at this time the diaphragms will operate as a constant pressure regulator. If the consumer attempts to operate appliances which will use more than the demand limit of fifty cubic feet per hour for example, the pressure in the chamber 73 will tend to fall to such a point that the diaphragm 74 with its weight will move into its lowermost position and at this time the pressure differential across the diaphragm 72 will tend to operate the diaphragm 72 independently of the diaphragm 74 whereby the mechanism will operate as a demand limiting meter. At this time the valve 60 is controlled solely by the diaphragm 72 and the latter operates entirely by virtue of the difference in gas pressure between chambers 52 and 73. The weight 96 is so selected that it will maintain approximately a differential of one-half an inch of water pressure on opposite sides of the diaphragm and therefore when a customer attempts to use appliances which will consume more gas than the demand limit, the pressure at the outlet 56 will be varied in operating the diaphragm 72 to deliver a volume of gas equal only to the demand limit. When the pressure in the outlet 56 begins to fall due to the demand limiting operation of the meter, the customer is warned that he is attempting to burn more than the demand limit and may thereby turn off some of the gas burning appliances to restore full pressure.

When it is desired to increase or decrease the demand limit it is only necessary to substitute orifice plugs 64 having different sizes of orifices 66.

It will be seen that I have provided an arrangement having not only the advantages pointed out above but one also adapted to use only well tried parts and mechanisms whereby the means for regulating the pressure, limiting the maximum demand and metering the volume consumed may all be combined in a

unitary structure which is compact, and easily manufactured.

It will be seen also that the arrangement according to my invention provides a rigid connection between the inlet and outlet whereby the thin casing of the ordinary "tin" house meter is effectively protected from damage in connecting the meter to and disconnecting it from the service pipes. Moreover, as all the apparatus is enclosed within one casing, the expense of connections is a minimum.

While I have illustrated and described in detail a particular embodiment of my invention, I do not limit myself to details of the drawing or description except in so far as such details are essential to the novelty of the appended claims.

I claim:

1. In a meter the combination of a casing, a volumetric measuring mechanism in the casing, means in the casing for restricting the rate of flow of fluid through the mechanism to a predetermined maximum, and means in the casing for delivering fluid from the casing at constant pressure.

2. In a meter the combination of a casing, a fluid inlet and outlet in the casing, a volumetric measuring mechanism in the casing, a flow restriction in the casing and in the path of flow of gas through the meter in series with the path of flow through the measuring mechanism, means including said flow restriction for limiting the flow of gas through said measuring mechanism to a predetermined maximum and means responsive to the pressure at the meter outlet for controlling the flow of fluid through the meter.

3. In a meter the combination of a casing, a fluid inlet and outlet in the casing, a volumetric measuring mechanism in the casing, a flow restriction in the casing and in the path of flow of gas through the meter in series with the path of flow through the measuring mechanism and means responsive to the pressure differential through said mechanism and restriction, for restricting the rate of flow of fluid through the meter to a predetermined maximum.

4. In a meter the combination of a casing, a fluid inlet and outlet in the casing, a volumetric measuring mechanism in the casing, a flow restriction in the casing and in the path of flow of gas through the meter in series with the path of flow of gas through the measuring mechanism, means responsive to the pressure differential through said mechanism and restriction for restricting the rate of flow of fluid through the meter to a predetermined maximum, and means responsive to changes of pressure at the outlet for maintaining the outlet pressure constant while delivering fluid up to the predetermined maximum.

5. In a meter the combination of a casing,

a fluid inlet in the casing, said casing having a fluid outlet provided with a flow restricting device, a volumetric measuring mechanism in the casing arranged to deliver gas from said inlet to said outlet and means mounted in the casing and responsive to the difference in pressure between the pressure at the inlet of said mechanism and the pressure in the fluid on the outlet side of said restriction for controlling the flow of fluid through the meter.

6. In a meter the combination of a volumetric metering mechanism, an inlet and outlet for the meter, an orifice member through which the gas flows in series with said mechanism, a valve governing the flow of gas to said mechanism and orifice member, and means connected with the valve and subjected to the pressure of the gas flowing through the meter whereby said valve is controlled either by the difference between the gas pressure at the meter outlet and the atmospheric pressure or by the drop in the gas pressure across both said mechanism and said orifice member depending on the rate of flow through said metering mechanism.

7. An apparatus of the class described comprising in combination, a pressure operated volumetric meter mechanism, an inlet valve regulating the flow of gas to said mechanism, an orifice member receiving gas from said mechanism, a pair of diaphragms for regulating said inlet valve, said diaphragms enclosing a space between them, means for operating said valve from said diaphragms, the apparatus being so constructed and arranged that one of said diaphragms is exposed to the gas pressure at a point intermediate said valve and said mechanism and the other of said diaphragms is weighted and exposed to the atmosphere, said weighted diaphragm having lost motion connection with said means, and means whereby the pressure between said diaphragms is maintained equal to that on the outlet side of said orifice member.

8. The combination of a meter casing containing a volumetric metering mechanism having a chamber in its upper portion, a casting above said casing and having a chamber therein in free communication with said chamber in the meter casing, said casting having inlet and outlet connections thereon, a diaphragm in said casting exposed to said second mentioned chamber, a second diaphragm spaced above said first mentioned diaphragm, an inlet valve, means whereby said valve is controlled by said diaphragms, and a connection between said outlet and the space between said diaphragms.

9. The combination of a meter casing containing a volumetric metering mechanism, and having a chamber in its upper portion, a casting above said casing and having a chamber therein in free communication with

said chamber in the meter casing, said casting having inlet and outlet connections thereon, a diaphragm in said casting exposed to said second mentioned chamber, a second diaphragm having a weight thereon and spaced above said first mentioned diaphragm, an inlet valve, means whereby said valve is controlled by said diaphragms, and a connection between said outlet and the space between said diaphragms, said casting having an orifice therein through which the gas passes intermediate the meter mechanism and the said connection to the inter-diaphragm space.

10. The combination of a volumetric metering mechanism, an inlet and an outlet for said mechanism, an orifice member between said inlet and said outlet and through which the gas passes in series with said mechanism, a combined pressure regulating and demand limiting valve controlling the flow of gas to said mechanism and said orifice, a pair of diaphragms, operating connections between said valve and said diaphragms and means whereby said diaphragms govern said valve either to produce a substantially constant pressure in said outlet or to limit the flow of gas depending upon the rate of gas flow through said mechanism and said orifice member, said means including pressure conducting connections whereby one of said diaphragms is subjected to the pressure drop across said mechanism and said orifice member, and pressure conducting connections whereby the other diaphragm is subjected to the pressure difference between the atmosphere and that on the first diaphragm.

11. The combination of a volumetric metering mechanism, a casing, an orifice member in said casing and through which the gas flows in series with said mechanism, a pair of operating members mounted to be moved by a gas pressure, and means whereby gas is supplied to said mechanism at substantially constant pressure while the rate of flow is below a given amount but whereby the flow is cut down when it tends to exceed said amount, said means including pressure conducting connections whereby an operating member is subjected to the pressure drop across said mechanism and said orifice member and pressure connections whereby the other operating member is subjected to the pressure difference between atmosphere and that on the first operating member.

12. The combination of a casing having a volumetric metering mechanism therein and having a valve chamber in its upper portion, a casting above said casing having an inlet and outlet and having a chamber connected to said inlet and in free communication with said valve chamber, a pair of diaphragms in said casting, said casting and said diaphragms being so constructed and arranged that the diaphragms are spaced one above the other, the lower of said diaphragms is ex-

posed on its under surface to the gas pressure in said chambers and the upper of said diaphragms has its upper surface exposed to the atmosphere, said diaphragms being weighted, the upper diaphragm being weighted relatively heavier than the lower, a combined pressure regulating and demand limiting inlet valve for controlling passage of gas from said inlet to said chambers, connections between said diaphragms and said valve for operating said valve, said connections having a lost motion engagement with said upper diaphragm, and a gas connection between said outlet and the space between said diaphragms.

13. The combination of a casing having a volumetric metering mechanism therein and having a valve chamber in its upper portion, a casting above said casing having an inlet and outlet and having a chamber connected to said inlet and in free communication with said valve chamber, a pair of diaphragms in said casting, said casting in said diaphragms being so constructed and arranged that the diaphragms are spaced one above the other, the lower of said diaphragms is exposed on its under surface to the gas pressure in said chambers, and the upper of said diaphragms has its upper surface exposed to the atmosphere, said diaphragms being weighted, the upper diaphragm being weighted relatively heavier than the lower, a combined pressure regulating and demand limiting inlet valve for controlling passage of gas from said inlet to said chambers, connections between said diaphragms, and said valve for operating said valve, said connections having a lost motion engagement with said upper diaphragm, a gas connection between said outlet and the space between said diaphragms, and an orifice member through which the gas flows in series with said volumetric mechanism and intermediate said mechanism and said connection to the inter-diaphragm space.

14. The combination of a volumetric metering mechanism, a demand limiting valve in series with said mechanism, means in series with said mechanism causing an increased drop in pressure with increased flow of gas, a diaphragm, means whereby said diaphragm is operated by the drop in pressure across both said mechanism and said means, and operating connections between said diaphragm and said valve.

15. The combination of a volumetric metering mechanism, a demand limiting valve in series with said mechanism, means in series with said mechanism causing an increased drop in pressure with increased flow of gas, a diaphragm, means whereby said diaphragm is operated by the drop in pressure across both said mechanism and said means, and means whereby said first mentioned means may be readily varied to vary

the point at which said valve operates to limit the flow of gas.

16. The combination of a volumetric metering mechanism, a demand limiting valve in series with said mechanism, an orifice member in series with said mechanism causing increased drop in pressure with increased flow of gas, a diaphragm, means whereby said diaphragm is operated by the drop in pressure across both said mechanism and said orifice member, operating connections between said diaphragm and said valve, and means whereby said orifice member may be readily changed to vary the demand limit.
17. The combination of a volumetric meter, valve means for controlling the flow of gas to said meter, a diaphragm, means including said diaphragm whereby said valve is controlled normally by the pressure on the meter, a second diaphragm, and means in-

cluding said second diaphragm whereby said valve is controlled during periods of maximum flow of gas by the difference between the pressure at the outlets of said meter and that intermediate said valve and said meter. 25

18. The combination of a volumetric meter, valve means for controlling the flow of gas to said meter, a flow restriction in series with said meter, a diaphragm, means including said diaphragm whereby said valve is controlled normally by the pressure on the outlet side of said meter, a second diaphragm, and means including said second diaphragm whereby said valve is controlled during periods of maximum flow of gas by a pressure equal to the sum of the drops of pressure through said volumetric meter and said flow restriction. 30 35

In testimony whereof I affix my signature.
ROBERT G. GRISWOLD.
